J. P. JOHNSON, OF MACON, ILLINOIS.

Letters Patent No. 71,623, dated December 3, 1867.

IMPROVEMENT IN CULTIVATORS.

The Schedule referred to in these Letters Patent and making part of the same.

TO ALL WHOM IT MAY CONCERN:

Be it known that I, J. P. JOHNSON, of Macon, in the county of Macon, and State of Illinois, have invented a new and improved Cultivator; and I do hereby declare that the following is a full, clear, and exact description thereof, reference being had to the accompanying drawings, making a part of this specification, in which—

Figure 1 is an elevation of one side of the machine, with portions of the wheel broken away to exhibit parts which are behind it.

Figure 2 is a plan view of the machine.

Figure 3 is an elevation of the rear end of the machine.

Similar letters of reference indicate corresponding parts in the several figures.

This invention relates to certain novel improvements on cultivators, wherein the ploughs or shovels are attached to a frame that is mounted on two wheels, so as to be drawn by two horses, and wherein a driver's seat is applied to said frame in a position which will allow the driver to guide the ploughs along the rows with his feet.

The object of my invention is to connect together plough or cultivator-beams, which are loosely hinged at their front ends to the carriage-frame by means of diagonal braces attached by loose connections to standards rising from said beams, and to apply foot pieces to the plough-beams in such manner that the driver, whilst riding upon the machine, can readily guide the ploughs and control their movements along the rows with his feet, as will be hereinafter explained. Another object of my invention is to enable the driver to raise or lower the ploughs or shovels with his feet, in a machine combining the above-mentioned elements, by suspending the rear ends of the shovel-beams from the axle of the transporting-wheels, by means of chains passing over pulleys, and provided with stirrups for the feet of the driver, as will be hereinafter explained.

To enable others skilled in the art to understand my invention, I will describe its construction and operation.

In the accompanying drawings, A represents the axle of two transporting-wheels B B, which axle is mainly of wood, its ends being metal pieces, which are bent so as to raise the wooden portion considerably above the hubs of the said wheels. This will leave plenty of room for the axle to pass unobstructedly over plants undergoing cultivation. The draught-pole C is secured rigidly to the middle of the length of the axle A, and extends in rear of this axle some distance, receiving upon its rear forked end a seat, D, upon which the driver sits to manage the machine. In front of the axle C is a transverse beam, E, which is secured rigidly to the draught-pole C, so as to project equal distances from both sides thereof. To this beam the single-trees a a are attached, and near its ends strong pendants are secured, extending downward some distance, as shown at b b. To these pendants b the forward ends of the two forked plough or shovel-beams F F are attached by means of loose joints or links c c, which will allow the said beams to vibrate freely in every desired direction. These forked beams are curved at their rear ends, and have shovels or ploughs d d, of any suitable form, secured firmly to them, as shown in the drawings. Between the two forks of each plough-beam F, a standard, G, is rigidly secured at its lower end by means of a transverse bolt, e, which also secures firmly in place, on the inner side of each beam, a step, g, for the foot of the driver. The standards G G rise some distance above the carriage-frame of the machine, and are connected together by means of two diagonal braces G' G', which are crossed and pivoted together at the middle of their length, as clearly shown in fig. 3. These cross-braces are attached to the standards G by means of links or eye-bolts, h, which allow the driver to raise or lower or to move the ploughs in any desired position while the machine is being drawn along. Several extra holes are made through the ends of the braces G' G' for allowing the eye-bolts on the braces to be adjusted nearer or further from the central pivot of these braces. The curved braces j j, which are secured to the beams F and to the standards, serve to stay these standards against forward or backward strain. The plough-beams F F are suspended from the axle A by means of chains t t, which pass through eyes affixed to the axle A, and are carried over grooved pulleys upon the rear side of this axle. These chains have stirrups s s attached to their pendent-ends, into which the driver puts his feet when he desires to raise the ploughs free from the ground. The driver's seat D is located upon the rear end of the draught-pole C, in rear of the axle A, so that the driver, whilst sitting upon his seat, can move and control the movements of the ploughs with his feet, while his hands are free, and also so that the driver can conveniently get on and off his seat while the machine is in motion.

I have shown that the two forked plough-beams are loosely hinged to the front part of the machine, so as to allow their rear ends to have a free lateral and vertical play; also that the rear parts of these beams are connected together by means of diagonal braces, so attached as to allow the driver to adjust the ploughs as he may desire during the forward movement of the machine. These loose connections allow the plough-beams to be spread apart, and to be adjusted toward each other; and while this is the case the braces G' G' and their standards prevent the plough-beams from turning about their front joints, and keep the ploughs always in an upright position.

Having described my invention, what I claim as new, and desire to secure by Letters Patent, is—

1. The attachment of the forked plough-beams F F to pendants b b by means of loose joints c c, and the employment, in combination therewith, of the standards G G and diagonal braces G' G', steps g g, and driver's seat D, arranged and operating substantially as described.

2. In combination with plough-beams F, which are attached by loose connections at their forward ends, and sustained in position by diagonal braces G' G' and standards G G, I claim the employment of suspending-chains and stirrups for enabling the driver to raise and lower the ploughs, substantially as described.

J. P. JOHNSON.
